UNITED STATES PATENT OFFICE.

JOHN M. WADDELL, OF GREENFIELD, OHIO.

SUPPORT FOR BOX-LIDS.

1,399,830.

Specification of Letters Patent. Patented Dec. 13, 1921.

Application filed June 17, 1921. Serial No. 478,429.

To all whom it may concern:

Be it known that I, JOHN M. WADDELL, a citizen of the United States of America, and a resident of Greenfield, in the county 5 of Highland and State of Ohio, have invented a new and useful Improvement in a Support for Box-Lids, of which the following is a specification.

An object of my invention is to provide 10 means to support box lids, especially the lids of cigar boxes, at an angle to the body of the box.

Another object of my invention is to provide means for the purpose stated that will 15 not interfere with the positioning of boxes adjacent one another.

Another object is to provide means for the purposes stated that is simple in construction, application and inexpensive.

20 Another object is to provide means for the purposes stated that may also be used to support price tags, or similar articles, in such relation to the box as to be on display.

These and other objects are attained by 25 the means described herein and disclosed in the accompanying drawings, in which—

Figure 1 is a perspective view of a cigar 30 box, parts being broken away, having a device embodying my invention mounted thereupon.

Fig. 2 is an enlarged perspective view of a support embodying my invention.

Fig. 3 is a development of a support shown in Fig. 2.

35 The support of my invention comprises a substantially cylindrical tube A, preferably of a material such as spring brass, having a slot a extending longitudinally therethrough. The slot a is substantially parallel with the axis of the tube. The slot a is enlarged at its lower end, whereby a shoulder a' is formed intermediate the upper end a² and the lower end a³ of the tube. A second slot a⁴ is formed in the lower end of the 40 tube and is spaced from the enlarged portion of the slot a by a strip a¹¹ formed between the slots. A shoulder a⁵ bounds part of the uppermost end of the slot a⁴ and is disposed from the lower end a³ of the tube 45 at a distance substantially equal to that at which the shoulder a' is spaced from the lower end a³ of the tube. Beyond the shoulder a⁵ the slot a⁴ extends upwardly or longitudinally of the tube to a short distance 50 so as to form a shoulder a⁶. From the shoulder a⁶ the side wall a⁷ bounding the slot a⁴

extends uninterruptedly to the bottom or lower end a⁸ of the tube. The shoulder a' is rounded adjacent the reduced portion of the slot a as shown at a⁸. The corner a⁹ 60 and a¹⁰ formed upon the strip a¹¹ extending between the slots a and a⁴ are slightly rounded. The corner a¹³ is also rounded. The article is applied as follows:

The lid b of the box B is moved to a position so that the lid extends at substantially right angles to the normally closed position of the lid. The tube A is then mounted upon the forward or upper end of the lid in relation thereto substantially as 70 shown in Fig. 1, except that in the referred to view the tube is disposed at the lower or rear end of the lid, the lid extending through the longitudinal slot a in the tube. The tube is then moved downwardly until 75 the back b' of the box enters the enlarged lower portions of the slots a and a⁴, whereby the strip a¹¹ will assume a position interiorly to the box body b² as shown in Fig. 1, and the opposing strip a¹⁴ will assume a 80 position exteriorly of and to the rear of the box B. The uppermost portion of the slot a⁴ permits the tube to clear the upward projection b³ formed on the sides b⁴ of the box, which projection extends above the upper edge of the back b' of the box. In 85 cigar boxes the lid, when raised to the position described, assumes a position parallel with and disposed immediately behind the rear or outer surface of the rear wall b' of 90 the box. The tube serves to retain the lid b in this parallel relation with the back b' of the box.

When lids, such as b, are disposed at a position in front of the rear wall b' of the 95 box, the slots in the tube may be varied so as to accommodate this modification. In like manner the slots may be varied to accommodate a box in which the lid, when in its upright or extended position, is disposed 100 in alinement with the back b' of the box. A suitable display card such as C may be retained in engagement upon the forwardly exposed surface of the lid b by inserting the card between the edge a¹² of the tube 105 and the lid b.

What I claim is:

1. A box lid retainer comprising a tube having a slot substantially parallel with the axis of the tube and through which a box 110 lid and a portion of the box wall mounting the lid may extend, and having a second slot

through which the said box wall only may extend.

2. A box lid retainer comprising a tube having a slot substantially parallel with the axis of the tube, a shoulder formed upon the tube extending into the said slot, the slot being adapted to permit the lid of a box to be inserted into the tube and the shoulder being adapted to engage upon the box wall

supporting the lid, the tube having a second slot and a shoulder extending into the second slot, the second slot permitting the said box wall to extend into the tube and abut upon the second mentioned shoulder.

In testimony whereof, I have hereunto subscribed my name this 14th day of June, 1921.

JOHN M. WADDELL.
